(57) **CLAIM**

I claim the ornamental design for a swimsuit, as shown and described.

DESCRIPTION

FIG. 1 is a front view of a swimsuit on a model showing my new design according to the present invention.

FIG. 2 is a rear view of the swimsuit of FIG. 1.

FIG. 3 is a right-side view of the swimsuit of FIG. 1; and, FIG. 4 is a left-side view of the swimsuit of FIG. 1.

The broken lines formed by linear segments of equal length in FIGS. 1-4 are provided for environment only and form no part of the claimed design.

1 Claim, 4 Drawing Sheets

FIG. 1

FIG. 2

FIG. 3

FIG. 4
